United States Patent Office

Des. 191,787
Patented Nov. 21, 1961

191,787

CLIP

Ruth M. Heil, Cleveland, N. Dak.
Filed June 23, 1961, Ser. No. 65,704

Term of patent 14 years
(Cl. D17—3)

FIG-2

I claim:

The ornamental design for a clip, as shown.
